UNITED STATES PATENT OFFICE

1,967,905

WALL STRUCTURE

Carlisle K. Roos, Wheaton, Ill., assignor to United States Gypsum Company, Chicago, Ill., a corporation of Illinois

Application December 23, 1933, Serial No. 703,731

13 Claims. (Cl. 72—16)

This invention relates to fire resistant wall structures and is particularly adapted for use in dwellings and buildings having plastered walls and ceilings where the rigid requirements of building codes and ordinances must be met and at the same time satisfactory construction at reasonable cost must be provided.

A particularly desirable feature of the present invention is the provision of a heat resistant wall structure involving the use of reticulated or foraminated metal, such as so-called expanded metal lath and wherein means is provided, in conjunction and cooperation with such lath, for increasing the fire resisting and other advantageous characteristics of the wall structure.

It is an object of the present invention to provide a wall structure and plaster supporting element for cooperation with other elements therein whereby the escape of normal moisture through or from the wall under the influence of heat is retarded and whereby the major portion of the radiant energy will be reflected thereby providing a wall of great strength and high heat and moisture insulating characteristics.

A further object is to provide a wall structure combining an unusual number of desirable and advantageous characteristics without materially increasing the weight or thickness of the walls and, at the same time, enabling the ordinary workman to build a satisfactory wall in the usual well known manner and without the necessity of learning a new technique or acquiring special knowledge.

Further objects will be apparent from the specifications and the appended claims.

In the drawings:

Fig. 1 is a fragmentary perspective vertical section of a wall structure illustrating an embodiment of the invention.

Fig. 2 is a perspective view of one of the lath and illustrates the arrangement of the component parts thereof and the method of fastening them together.

Fig. 3 is a fragmentary vertical section through one of the lath in which a somewhat different type of foraminated metal is used.

Fig. 4 is a fragmentary transverse section through one of the lath in which expanded metal is used and in which the metal is indented and the fabric with foil backing is secured thereto at the indentations.

Referring to the drawings in detail, the embodiment illustrated therein, and particularly in Fig. 1, comprises a double wall structure including the usual vertical studding 1 which may be the

ordinary 2" x 4" material or any other suitable support ordinarily used in building construction.

In order to provide a suitable plaster support, sheets of specially constructed lath 2, such as illustrated in Fig. 2, are secured to the wall studding in the usual manner as by nailing or stapling and the usual plaster coating is applied thereto. In Fig. 1, a double wall construction is shown, and having a plastered inner surface and a brick veneer outer surface. This construction will be described in detail later.

Each lath 2 comprises a sheet of expanded, reticulated or foraminated metal 3 having secured to the back side thereof a sheet of fabric 4 which latter may be of a suitable material such as so-called kraft paper or chip paper.

Prior to the application of the fabric to the expanded metal, one of the surfaces of the fabric is covered with a metal coating 5, preferably aluminum foil, for purposes hereinafter specified. The coating 5 may be applied and secured snugly to the paper in intimate contact therewith and in any suitable manner, preferably by a suitable adhesive such as asphalt, sodium silicate solution, or a dextrine adhesive. The foil may be firmly secured to the board by these or other adhesives and by applying heat or pressure or both in a suitable and well known manner. The sheet of metallized fabric 4 is slightly smaller than the expanded metal lath as shown in Fig. 2, and is secured thereto by means of staples 6. The bight portion of the staple is preferably against the metallized side of the fabric and the prongs extend through the fabric and the mesh of the expanded metal and may be bent over and clinched on the mesh. The adjacent ends of the prongs may be given a slight locking twist as shown in Figs. 1 and 3 or may be merely clinched over the mesh as in Fig. 4.

In applying the fabric to the expanded metal lath the fabric is placed thereon with the foil side exposed and in alignment with one side and one end of the reticulated metal allowing a narrow strip of the metal at the opposite side and end to be exposed for overlapping of the lath. The reticulated or foraminated metal used may be any of the usual types used for metal lath, but is preferably expanded metal and may be provided with the usual ribs or corrugations if desired which may be of the type shown at 7 in Fig. 3, or with indentations 8 as in Fig. 4.

In securing together the component elements of the lath, the fabric is applied to that side of the foraminated metal sheet from which the corrugations or indentations extend, thereby pro-

viding portions between these corrugations or indentations spaced slightly from the fabric, whereby when plaster is applied to the expanded metal, it will completely fill the space between the mesh and the fabric thereby efficiently locking or keying the plaster coating in place. Even when expanded metal without ribs or other self-furring means is used portions of the mesh will normally be spaced somewhat from the paper backing.

10 This, and also the pressure of the workman on the plaster in the normal act of plastering, will cause the plaster to be effectively keyed to the mesh.

As previously mentioned, Fig. 1 illustrates a double wall construction having a brick veneer outer surface and a plastered inner surface, although a single wall structure will be satisfactory in many instances and the lath constructed as described herein may be used only on the plastered side of the wall and the other side may be of any desired construction.

In the double wall shown, the above described lath sheets 2 are secured to both sides of the studding 1 by means of suitable fasteners and 25 with the foil or metallizing coating adjacent the studding thereby providing a foil enclosed insulating air space in the wall. A plaster coating 9 is applied to the inner surface of the wall in the normal manner and a plaster coating 10 is applied to the outer surface simultaneously with 30 the laying of a brick veneer 11 whereby the brick veneer and the lath are all secured together by the plaster coating therebetween. The air space between the two heat reflecting foil coatings 35 assists in providing an efficient heat insulating, fire and moisture resisting wall structure.

The plaster coating is applied to the mesh with its fabric and foil backing, in a moist condition, and, when dried, the plaster is interlocked 40 with the mesh and also adheres snugly to the fabric backing thus assisting in strengthening the wall structure.

The metal foil 5, as previously stated, adheres 45 snugly to the paper backing and, being waterproof, effectively prevents the escape of moisture through the wall, this foil also being an efficient heat reflector with low emissivity, thus assisting in providing a wall with heat and moisture insulating characteristics of a high order.

50 The metallizing coat applied to the paper is preferably very thin aluminum, although other materials may be used. In any case a metal capable of providing bright surface is used in order that the heat reflecting characteristics of 55 such a surface may be taken advantage of. The amount of metal in such a coating is small, and little heat is thus lost either by conduction or by convection currents.

When a wall structure such as disclosed herein 60 is subjected to high temperature for a prolonged time, as in certain tests now required of building structures, the heat calcines the plaster beginning at the outer surface and progressing inwardly, but at a reduced rate by reason of the fact that the 65 heat required to dehydrate or calcine the plaster tends to prevent further rise of the temperature of the plaster until its calcination is completed.

Since calcined plaster is a good heat insulator, an appreciable time is required before the calcination reaches the stage and the plaster reaches 70 the temperature at which any effect on the paper or fabric backing of the lath is noticeable. As the temperature rises to the ignition point, the paper or fabric would ordinarily burst into a flame, 75 but by virtue of the covering of the calcined

plaster on one side and the foil covering on the other, excess of atmospheric oxygen to the paper or fabric is prevented with a result that only a sort of dry distillation takes place. This dry distillation results in the charring or carbonization of the paper or fabric converting the same into a more or less coherent layer of carbon which in itself has heat resistant value if the layer can be maintained in position in the wall. The foil coating 5 on the back of the fabric adheres closely to this carbonized layer and is secured, together with the fabric, to the reticulated metal by means of the staples 6. Also, the plaster, being more or less coherent even after calcination, is held in place between the mesh of the reticulated metal and the foil covered fabric, and as long as this covering of calcined plaster and a sufficiently large area of unbroken carbonized paper or fabric can be maintained in position, the fire will not penetrate the wall.

90 The foil coating has considerable strength particularly as it is secured to the fabric and adheres thereto even after carbonization of the fabric and calcination of the plaster. Carbonization of the fabric is retarded due to the fact that the moisture therein is retained by the foil backing; therefore, all of the moisture in the fabric and plaster must be given off through the plaster thereby delaying complete calcination and carbonization and materially lengthening the life of the structure.

100 Although a comparatively small number of the fastening staples 6 may be used for securing the foil covered fabric to the reticulated metal, the area between any four adjacent fasteners is relatively small and the fabric, as well as the plaster 110 between the fabric and reticulated metal, is retained in place for a maximum length of time even after prolonged exposure to high temperature, by the comparatively small, well secured areas of foil between the staples.

115 To assist in retaining the foil in place during and after carbonization of the fabric and to prevent the fasteners or staples 6 from cutting through the foil or fabric in the clinching process, washers 12 may be used and the prongs of the 120 staples passed therethrough, as shown in Fig. 4, in which is illustrated the same construction as in Fig. 2, except that the foraminated metal 3^a is provided with spaced indentations 8 to which the fabric and foil backing is secured and which provides a space 13 between the foraminated metal 125 and the backing which will be filled in the normal act of plastering thereby keying the plaster securely in place in the same manner as previously described.

130 A wall structure built in accordance with this invention is particularly efficient in that it provides, in a comparatively inexpensive easily built structure, a wall having great strength and resistance against shock as well as being proof against 135 wind and air infiltration and substantially a complete insulation against heat, cold, moisture, dust and vermin both large and small, as well as being an efficient fire retarder and an insurer against sudden changes of room temperature. 140 Other advantages might be enumerated, but it is obvious that in the practice of this invention, more desirable characteristics may be incorporated in a simple, inexpensive, and peculiarly efficient structure than has heretofore been possible in the art.

145 While only certain specific embodiments of the invention have been shown and described herein, it will be readily understood by those skilled in the art that changes and modifications in the de-

- fails of design and construction may be resorted to without departing from the spirit and scope of the invention as set forth in the appended claims. For instance, instead of using aluminum foil, a 5 relatively thin metallic covering of other types or materials may be used if desired. It will also be understood that the claims are not intended to be specifically construed except as required by the prior art, and that the terms used comprehend a 10 proper range of equivalents, e. g., the term "wall" including ceilings as well as vertical walls, etc.
- Having thus described my invention, what I claim and desire to secure by Letters Patent is:
1. A building wall structure comprising supporting members, plaster supporting foraminated metal sheets overlying a plurality of said supporting members and secured thereto with their rear surfaces facing hollow wall spaces, the rear surface of each sheet being substantially completely covered with a fabric secured thereto and having a heat reflective metal coating substantially coextensive and in intimate contact therewith on the side facing the wall space. 15
  2. A building wall structure comprising supporting members, plaster supporting foraminated metal lath secured thereto with their rear surfaces facing hollow wall spaces, the rear surface of each lath being substantially completely covered with a laminated fabric secured thereto and comprising a paper sheet coated with aluminum foil in intimate contact therewith on the side facing the wall spaces, said paper sheet and foil being substantially coextensive. 20
  3. A building wall structure comprising supporting members, plaster supporting laminated sheets secured thereto with their rear surfaces facing hollow wall spaces, said sheets comprising in the order recited a sheet of foraminated metal lath, a sheet of fabric secured to and substantially completely covering one side of said lath, and metal coating having high heat reflecting characteristics covering and adhering to the opposite side of said fabric, and facing said wall spaces, said fabric and metal coating being substantially coextensive. 25
  4. A building wall structure comprising supporting members, a plaster supporting laminated sheet secured thereto with its rear surface facing hollow wall spaces, said sheet comprising in the order recited, a sheet of expanded metal lath, a sheet of paper secured to and substantially completely covering one side of said expanded metal lath, and a heat reflective metal coating applied to the side of said paper opposite said metal lath and facing said wall spaces, said paper sheet and coating being substantially coextensive and said metal, paper and metal coating being secured together to form a unitary structure. 30
  5. A wall structure of the character described comprising supporting members, a plaster supporting laminated sheet secured thereto with its rear surface facing hollow wall spaces, said laminated sheet comprising a layer of paper, a layer of reflective metal adhering to one side thereof and facing said wall spaces, and a layer of expanded metal lath on the opposite side, spaced securing means securing said paper and said expanded metal together to provide comparatively small metallized paper areas between any four adjacent securing means, and a coating of plaster on said expanded metal and filling the space between said paper and the mesh of said expanded metal. 35
  6. A wall structure of the character described comprising supporting members, a plaster supporting laminated sheet secured thereto with its rear surface facing hollow wall spaces, said laminated sheet comprising a layer of paper, a layer of reflective metal adhering to one side thereof and facing said wall spaces, and a layer of expanded metal lath on the opposite side, spaced securing means securing said paper and said expanded metal together in a manner to provide comparatively small foil areas between any four adjacent securing means, and a coating of plaster on said expanded metal and filling the space between said paper and the mesh of said expanded metal. 40
  7. A laminated insulating plaster supporting lath for wall structure comprising, a sheet of foraminated metal, a sheet of semi-rigid fabric secured to one side thereof in a manner to allow the insertion of plaster therebetween to interlock with the foraminations of said metal, and a coating of metal having high heat reflecting characteristics and snugly adhering to the opposite side of said fabric and being substantially coextensive therewith, said foraminated metal, fabric and coating being held together to form a unitary structure. 45
  8. A laminated plaster supporting lath for a wall structure comprising, a sheet of expanded metal, a sheet of paper secured to one side thereof in a manner to allow the insertion of plaster therebetween to interlock with the mesh of said metal in the normal act of plastering, and a covering of aluminum foil snugly adhering to the side of said fabric opposite said expanded metal and being substantially coextensive therewith, said expanded metal, paper and foil being held together at relatively closely spaced points to form a unitary structure. 50
  9. A building wall construction having hollow wall spaces and comprising supporting members and plaster supporting lath secured thereto, said lath comprising a paper-like sheet of fibrous material having one face metallized and having its opposite face covered with expanded metal secured thereto and having portions of its mesh spaced from said fibrous sheet, said metallized face of said sheet of fibrous material facing said wall spaces, said fibrous material and expanded metal being held together at relatively closely spaced points to form a unitary structure. 55
  10. In a material for receiving and retaining a plaster covering, the combination with foraminated metal, of a paper backing sheet in close relation therewith and acting to close the clench of the plaster with the metal and to adhere snugly to the plaster, and a sheet of aluminum foil snugly adhering to the rear surface of the paper backing and being substantially coextensive therewith, said metal, paper and foil being held together at relatively closely spaced points to form a unitary structure. 60
  11. A building wall structure comprising supporting members, a covering of plaster-supporting foraminated metal over said supports, the rear surface of said foraminated metal being substantially completely covered with fabric secured thereto, a coating of plaster on said foraminated metal and in intimate contact with said fabric, and a substantially continuous heat reflective metal coating secured on the rear surface of said fabric and substantially coextensive therewith and arranged to retard the escape of the water of crystallization under the influence of heat. 65
  12. In a material for receiving and retaining 65

15 a plaster covering, the combination with a fibrous
backing sheet, relatively closely spaced metallic
reinforcement intimately associated with said
fibrous backing sheet and adapted to become
5 embedded in plaster applied to one side of said
sheet, and a coating of metal having high heat
reflecting characteristics snugly adhering to
the opposite side of said sheet and being substan-
tially coextensive therewith, said reinforcement,
10 sheet, and coating being held together to form
a unitary structure.

13. In a wall structure of the character de-
scribed, comprising supporting members, a plas-
ter supporting element secured thereto with its
15 rear surface facing hollow wall spaces, said ele-
ment comprising a fibrous backing sheet, a coat-
ing of metal having high heat reflecting charac-
teristics adhering to and substantially coexten-
sive with one side of said sheet and in intimate
80 contact therewith and facing said wall spacing,
and a relatively closely spaced metallic rein-
forcement intimately associated with said fibrous
sheet and adapted to become embedded in plas-
ter applied to one side of said sheet, said sheet,
85 metallic coating, and reinforcement being se-
cured together to form a unitary structure.
